E. G. STAUNTON

WALL PAPER ROLL

Filed Oct. 8, 1923

FIG. 2.

INVENTOR.

E.G. Staunton.
BY J. Edward Maybee.
ATTY

UNITED STATES PATENT OFFICE.

EDMUND GIFFORD STAUNTON, OF TORONTO, ONTARIO, CANADA.

WALL-PAPER ROLL.

Application filed October 8, 1923. Serial No. 667,088.

To all whom it may concern:

Be it known that I, EDMUND GIFFORD STAUNTON, of the city of Toronto, in the county of York, Province of Ontario, Canada, a subject of the King of Great Britain, have invented certain new and useful Improvements in Wall-Paper Rolls, of which the following is a specification.

This invention relates particularly to the wrapping of rolls of wall paper which are provided with what are known as semi-trimmed selvages, that is, margins partly severed so that they may be torn off when the paper is to be hung. To protect the partly trimmed margins, rolls of such "semi-trimmed" paper are usually sent out with the ends taped with strips of gummed paper, and frequently also with a band or tape about the middle intended to prevent the accidental tearing of the exposed end of the web of paper. Such a roll possesses at least two well marked defects. In the first place, it is impossible to see the pattern of the paper and there is therefore a strong temptation for any one handling the roll to tear back the exposed end of the web and, once this web is torn, it is very liable to continue tearing back with constant handling when in stock. In the second place, despite the taping, the exposed end of the web is liable to tear accidentally, and this tearing is apt to extend back as suggested above and spoil an appreciable part of the paper. My object therefore is to devise better protection for the exposed end of the web, and also to provide means for displaying the pattern of the paper and to do this without adding appreciably to the cost of production of the roll either for material or for labor.

I attain my object by applying over the exposed web end one or more pieces of paper cut from paper similar to that contained in the roll, and which may be termed samples.

In one form a single rectangular strip is secured by a suitable adhesive all along the exposed web end, and is overlaid by the end tapes. In another form a plurality of separate samples are similarly secured along said web end, none of which need underlie the end tapes. In yet a third form the samples are formed of ungummed paper and underlie the tapes aforesaid. These ungummed samples are so shaped and applied that their greatest extension lengthwise of the roll is along the line of the exposed end of the web, while they extend a material dis-

tance round the roll under the bands. The best results are attained if all parts of the sample pieces, when it is laid flat, are substantially contained within a circle struck from the center of the sample and touching its points of greatest extension, which must be directed either substantially circumferentially or lengthwise of the roll. A substantially diamond-shaped form gives very satisfactory results, though the sides need not be straight lines, and circular or oval forms also give good results.

I find that the stiffness given the sample pieces by their curvature round the roll is sufficient to cause them to closely hug the roll and bind down the edge of the web despite the fact that no adhesive material is used except on the bands which hold them in place. This is of very great importance in the production of the roll, as the only extra operation in the taping of the rolls is the dropping of the sample pieces on the paper tapes and, as this is done at a time when the operator would otherwise be idle, the labor cost is not increased. The only added cost therefore in the production of the roll is the cost of producing the sample pieces which is practically negligible.

The invention is illustrated in the accompanying drawings in which—

Fig. 1 is a side view of a roll of wall paper wrapped in accordance with my invention;

Fig. 2 a side view of a modification;

Fig. 3 a side view of a further modification;

Fig. 4 an end elevation of a wrapping tape and sample piece such as shown in Fig. 3 as they would appear in position on a roll of paper, their thickness being exaggerated;

Fig. 5 a plan view of the form of sample piece shown in Fig. 3; and

Fig. 6 a similar view showing various modifications.

In the drawings 1 represents the exposed end of the web of paper forming the roll.

In Fig. 1, I show a rectangular sample piece 3, which is secured by an adhesive along the exposed web end. The ends of this strip are secured under the gummed paper bands or tapes 2 which are applied about the ends of the roll. With this arrangement the web end is perfectly protected and the pattern of the paper well shown. If more of the pattern lengthwise of the paper is required to be shown without using too much paper, a plurality of separate sam-

ple pieces may be used, which, if made of diamond shape, can be cut without waste, and in the aggregate contain no more paper than the continuous strip. See Fig. 2.

5. When the lowest possible cost is the desideration, I employ a gummed tape intermediate the ends, and apply under the said middle tape or band a sample piece 3, preferably diamond-shaped, as such pieces can be
10 cut without waste and without the use of special cutting dies. This piece is without any adhesive, and is held in place by the overlying tape. It is positioned as shown with its diagonals extending, one circumferentially and the other lengthwise of the roll over the end of the web and, owing to its curved form, it hugs the roll tightly at all points and presents no edges or corners liable to catch on projecting parts when the
15 roll is turned in a bin or otherwise handled. See Fig. 3.

For extra safety where the slight extra expense is not a consideration, two intermediate bands and sample pieces may also be
20 used, practically entirely protecting the web end and giving a better showing of the pattern of the paper than that given by a single piece.

In Fig. 4 I show how the shape of the
25 sample piece may be varied and more or less satisfactory results attained. A, B, C, D is a square in which is inscribed a circle E. The square form, unless used as a diamond, is inadmissible, as the corners cannot be
30 caused to hug the roll closely. The circular form is good, and also any form approximating the circle, such as the ellipse G. The octagonal form, obtained by cutting off the
35 corners of the square along the lines F F, is not quite so good.

In all cases the sample should preferably be applied, if it departs much from a circular form, with its greatest extension either approximately parallel to the axis of the roll or also substantially at right angles thereto.

When a sample is so arranged, it follows

that substantially all parts of its edges are inclined to the axis of the roll both circumferentially and longitudinally and it is this double inclination which causes the piece to lie so closely to the surface of the roll that it is not easily caught and torn, though only held on the roll by its circumferentially extended middle portion.

What I claim is:—

1. A roll of wall paper having a separate sample piece of paper positioned over its exposed web end; and an adhesive band extending circumferentially of the roll and securing said sample piece in place, said sample piece, when in position, having substantially all parts of its edges inclined to the axis of the roll both circumferentially and longitudinally.

2. A roll of wall paper having a separate diamond shaped sample piece positioned over its exposed web end with its diagonals extending circumferentially and longitudinally of the roll; and an adhesive band extending circumferentially of the roll and securing said sample piece in position.

3. A roll of wall paper provided with a plurality of separate sample pieces of paper positioned over its exposed web end, each sample piece, when in position, having substantially all parts of its edges inclined to the axis of the roll both circumferentially and longitudinally, said sample pieces being secured in position on the roll by their circumferentially extended middle portions.

4. A roll of wall paper provided with a plurality of separate diamond shaped sample pieces positioned over its exposed web end, each with its diagonals extending circumferentially and longitudinally of the roll, said sample pieces being secured in position on the roll by their circumferentially extended middle portions.

Signed at Toronto, Canada, this 1st day of October, 1923.

EDMUND GIFFORD STAUNTON.
